DESIGN FOR A BOOK END

Fred M. Torrey, Chicago, Ill., assignor to Plasto Manufacturing Company, Chicago, Ill., a co-partnership comprised of Joseph Borowitz and Louis Hochstadter

Application April 2, 1946, Serial No. 128,197

Term of patent 3½ years

(Cl. D33—1)

To all whom it may concern:

Be it known that I, Fred M. Torrey, a citizen of the United States and resident of Chicago, in the county of Cook and State of Illinois, have invented a new, original, and ornamental Design for a Book End, of which the following is a specification, reference being had to the accompanying drawing, forming a part thereof.

Fig. 1 is a side elevational view of a book end, embodying my new design.

Fig. 2 is a top plan view thereof.

Fig. 3 is an end view thereof.

Fig. 4 is a view showing the other end of the book end.

I claim:

The ornamental design for a book end, substantially as shown.

FRED M. TORREY.
